UNITED STATES PATENT OFFICE

2,137,520

VACUUM BREAKER

Roy H. Zinkil, Oak Park, Ill., assignor to Crane
Co., Chicago, Ill., a corporation of Illinois

Application August 8, 1935, Serial No. 35,322

14 Claims. (Cl. 4—70)

More particularly, this invention relates to that type of device known to those skilled in the art as vacuum breakers and especially to such form which is particularly suitable for use with plumbing fixtures such as closet bowls and the like, to prevent any reverse flow caused by back siphonage and thereby contaminating the fresh water supply creating an extremely dangerous and insanitary condition even to such extent as to precipitate epidemics involving serious illness.

Therefore, it is one of the more important objects of this invention to provide for a vacuum breaker which may be conveniently made integral with a water closet or any similarly used fixture without requiring the use of any moving parts and without any necessity for providing for a spill-over or a drain from the vacuum breaker other than through the normal openings through which the water flows to flush the fixture. More specifically, the vacuum breaker employing my invention is so constructed that there is no need for providing any special drain channels to let the water flow from the vacuum breaker unit to the closet proper.

It is another object to provide a vacuum breaker preferably integral with the fixture and which is so arranged that the air vents are positioned above the highest possible water level attainable within such fixture with which the vacuum breaker may be employed. By the expression "highest possible water level attainable within such fixture" is meant that under no circumstances short of flooding the room itself to a considerable depth, as for example, above the rim of the fixture, is it possible for the flushing supply and venting means within such fixture to be reached by contaminative water.

It is conceded that in the construction of a device of this character, care must be taken to provide for the supply orifice thereto being sufficiently removed above the highest possible water level attainable within the fixture so that upon the occurrence of a vacuum or reverse flow, sufficient air is admitted to prevent back siphonage.

More specifically, the baffle together with its aperture must be so positioned as not to allow for any possibility of reverse flow due to the vacuum or suction pull created within the lines and also prevent outwardly splashing spray during the flushing operation which might be termed "spitting". This necessitates positioning of the said orifice so as to allow for an air gap between it and the surface of the highest water level attainable and sufficient to prevent any liquid connection whatever or back flow therethrough.

Another important object is to provide for the type of device in which several of the parts may be made of the material of which the fixture itself is composed, as for example, porcelain or china, or earthenware, and the remaining parts may be made of conveniently machineable metallic materials.

Another important object is to provide for a construction which is so arranged as to permit the axial alignment of the respective fluid passages therewithin, thus expediting freedom of flushing flow, with a minimum of surface resistance, and also obtaining the maximum amount of kinetic energy from the water in its passage to the jet channel of the closet bowl, for example.

Another object lies in the provision in a vacuum breaker of the type described in which the respective ports or passages through which the flushing fluid may pass are in axial alignment, and one of the passages leads to the water supply nozzle. The lowermost one provides the necessary inlet to the channel of the fixture supplying the main jet, and the one positioned therebetween may also function as a baffle.

Another important object is to provide for a construction in which relatively high flushing velocity may be maintained with a comparatively small inlet supply. Another important object is to provide for a vacuum breaker preferably integral with the fixture having a hooded construction over the vent openings so as to conceal the latter from normal view and also to prevent the entry of foreign matter therewithin.

Another important object is to provide in a vacuum breaker of this type a construction in which the air vents in the breaker have an area many times greater than that of the area of the flush pipe inlet.

Another object is to provide a construction in which a spray baffle within the breaker serves to prevent slight "spitting" into atmosphere of the water during the flush.

Other objects and advantages of the invention will become apparent upon proceeding with the following description in connection with the drawing, in which

Fig. 1 is an exterior side view of a closet bowl illustrating a preferred positioning of an integral vacuum breaker thereon.

Fig. 2 is a fragmentary sectional assembly view of the vacuum breaker proper with relation to the rim supply and jet inlet, respectively.

Fig. 3 is a sectional view taken on line 3—3 of Fig. 2.

Fig. 4 is a fragmentary sectional view of a

modified form of my invention, in which the several internal parts as the throat and baffle, as distinguished from Fig. 1, are made integral with the bowl.

5 Similar reference characters refer to similar parts in the various views.

Referring specifically now to Fig. 2, the closet bowl 1 which may be of any conventional type, such as the siphon jet, for example, is provided with the extension housing or enclosure 2 preferably but not necessarily made integral therewith, having a hood or cover 3 with overhanging eaves or extensions 3a supported upon the rib 4 at the rearward portion and upon the forward wall 1b thereof, respectively, forming therebetween the air vent openings 5a for purposes hereinafter to be described in greater detail, and with an upward extending wall 5 serving as the lower limit of such vents 5a.

20 The lower portion of the peripherally formed extension wall 2 is provided with a transversely positioned baffle 6 having an upper surface 6a sloping slightly downwardly and inwardly toward its center portion from its peripheral extremities 25 and having a central aperture 7 serving as a drain for such water which may accumulate during the course of flushing. The baffle 6 for reasons hereinafter explained is preferably positioned so as to be beyond the highest possible 30 water level attainable within the bowl proper and as a consequence is positioned substantially above the upper surface of the rim 8.

The hood or cover 3 is provided at its upper surface with a nozzle member 9 suitably threaded 35 as at 9a for convenient attachment to the usual inlet supply pipe (not shown) as may be required, and also for the purpose of attachment to the hood, as will hereinafter be described. As shown in Fig. 2, the hood 3 is provided with an 40 opening 11 preferably tapered on its periphery so as to provide for a joint as at 12 with an annularly shouldered compressible gasket 13, the latter having a flanged lip, a portion of which normally is supported upon the annular shoulder 45 of the housing 3, and the other being inserted between the tapered peripheral clearance provided by the walls of the tapered aperture 11 and the shoulder 9b of the nozzle member 9. A threaded nut or washer 14 provides the means 50 for exerting the desired compression therebetween so as to form a normally fluid tight joint.

It is of course apparent that the detailed manner herein described in making up the foregoing joint may be modified considerably, and further 55 that per se it forms no significant part of this invention.

The lower portion of the nozzle member 9 is 60 preferably provided with a throat portion 9c which directs the flow of water therefrom in a converging stream possessing thereby increased velocity through the preferably slightly enlarged aperture 7 of the baffle 6 and thence into the aperture 15 of the jet channel 16 of the closet 1. The respective flow ports 9c, 7 and 15 are 65 preferably arranged in axial alignment so that frictional resistance to stream flow is reduced to an absolute minimum, but at the same time, properly spaced with air gaps so as to provide a positive assurance of venting from the atmosphere to prevent back siphonage.

70 The flushing water from a flush valve or tank (not shown) suitably positioned above the inlet of nozzle member 9 discharges downwardly 75 through the reduced aperture 9c and issues from

mouth 9e in a stream which projects through port 7 and into the channel 16 through port 15. A slight divergence or natural spread of the stream outwardly from the path of normal flow takes place below port 7 and produces a slight 5 spill-over or accumulation of water within space 19 in a preferred embodiment leading to the rim channel 1a of the bowl and serving thereby as a secondary flushing means for supplying water to rim of the closet 1, while the channel 16 leads 10 directly to the jet (not shown) of the bowl and accomplishes the principal or primary flush therewith by what is termed a syphonic jet action. Of course, the latter action will vary depending upon the type of closet bowl selected for 15 the installation.

It is apparent that any water which might accumulate, however slight, within the enclosure 17 will, because of the previously mentioned inwardly sloping surface 6a, drain by gravity toward its central portion and flow into the aperture 7.

Since the flushing water is discharging at relatively high velocity through the restricted passage 7, it is also obvious that a pronounced 25 ejector or aspirating effect is produced by reason of the air drawn in through the vents or ports 5a and which makes frictional contact with the flushing stream emerging from the mouth 9e of the nozzle member 9 thereby causing a certain 30 degree of turbulence and a mixture of air and water, particularly below the baffle 6, as more clearly shown in Fig. 3. This mixture of air with water is quite as effective as a corresponding 35 volume of water alone for flushing, thus resulting in a substantial economy in the amount of water ordinarily necessary for such flushing purposes.

Preferably at a position annularly surrounding the lower shoulder 9d and abutting against the 40 surface 9b, the downwardly extending and preferably cylindrically formed baffle 18 encloses the port 9c of the nozzle member 9, serving thereby as a restraining means against any outward passage of spray or droplets of water emanating at 45 high velocity from the port 9c. The lower limit of the baffle 18 may obviously extend to a level considerably lower or even higher than as illustrated, depending upon the service condition of the installation, having in mind that the principal 50 purpose of the baffle 18 is to reduce to a minimum the possibility of spray or random droplets splashing outwardly into the atmosphere, which latter condition is objectionable and insanitary and is known to those skilled in the art as "spitting". 55

Directing attention to Fig. 4, embodying an illustration which shows a modification featuring an integral construction, that is one in which the lower extending converging nozzle throat 9c and the surrounding peripheral baffle 18 are made 60 preferably integral with the closet or similar plumbing fixture with which the invention is associated. The spud or tailpiece 20 preferably threaded as at 20a and having a flared end abutting within the integral structure may then be joined in a manner similar to that described in connection with Fig. 2.

In explaining the operation of my invention, let it be assumed that a supply fixture, as for example a flushing valve or a tank connected by 70 the conventional tubing to the upper end of the nozzle member 9, has been actuated thus creating the flow of the flushing stream downwardly into the throat 9c and into the apertured passage 7 of the baffle 6. Such stream flow being under 75

relatively high velocity, as previously mentioned, tends to draw the air inwardly from the atmosphere through the aforementioned ports 5a. The incoming air through the ports 5a is drawn in from the surrounding atmosphere and the path of the air taken in is that as indicated by the arrows shown, and as previously stated, causing a certain degree of turbulence and a mixture of water and air which is effective in contributing to the efficiency of the flush as well as in economizing in the amount of water ordinarily necessary for flushing purposes.

Thus, in the event that a vacuum should be created within the supply lines which might be traceable to a variety of causes, as for example, in shutting off a valve in the fresh water supply line or else from a relatively heavy consumption of water at a lower level, it is readily apparent that by virtue of my invention it is absolutely impossible for any reversal of flow to occur within the fixture or for the liquid level to rise therein to any noticeable height so as to enter into the fresh water supply line. This condition is obtained by reason of the fact that the ports or vents 5a being of a generous size and always open to atmosphere, provide a full and free inward air flow, to prevent the formation of any vacuum in chamber 4. Consequently no water can be pulled (sucked) up from orifice 7 to nozzle 8e.

It is further apparent of course that the modifications are numerous which may be resorted to without departing from the invention herein described. I desire therefore to be limited only to the extent of the claims appended hereto, interpreted in view of the prior art.

I claim:

1. In an air relieving means of the character described, comprising in combination a fixture, a plurality of restricted ports in axial alignment, the latter constituting substantially vertical directional flushing means to the said fixture, a substantially horizontally extending baffle positioned transversely between said ports and having upon its upper surface inwardly sloping drain means for water accumulation during the flushing of said fixture, the said drain means discharging into the said axially aligned ports, the said baffle being positioned above the highest water level attainable within said fixture, a housing integral with the said fixture enclosing the said ports and the said baffle, the said housing comprising venting means to atmosphere in communication with the said ports.

2. In an air relieving means of the character described, comprising in combination a fixture to be flushed, a plurality of flushing ports in axial alignment and of substantially uniform size, an intermediate baffle positioned transversely between said ports and having an aperture in substantial axial alignment therewith, a housing integral with said fixture enclosing said inlet supply ports and said baffle, a coaxial throat portion projecting within said housing, annularly positioned baffle means around said throat portion, the said housing comprising vent openings to atmosphere positioned above the highest possible water level attainable in said fixture.

3. In a vacuum breaker, comprising in combination a fixture to be flushed, a plurality of coaxial flushing ports, a baffle positioned transversely between said ports and having an aperture in substantial axial alignment therewith, the said baffle being positioned above the highest water level attainable within said fixture, a vent-

ed housing integral with such fixture enclosing the said ports and said baffle, a coaxial throat portion within said housing and integral therewith, and an annular substantially coaxial baffle surrounding said throat portion.

4. In a vacuum breaker, comprising in combination a fixture having a plurality of ports in substantial axial alignment, the latter constituting flushing means for the said fixture, a spud projecting from the uppermost of said ports, an annular baffle surrounding said spud, the said spud and the said annular baffle being attached to the said vacuum breaker, a horizontal baffle positioned between said ports and having an aperture in axial alignment therewith, a housing enclosing said ports and the said baffles, the said housing having vents in communication with the said ports above the highest attainable water level within the said fixture.

5. In a vacuum breaker, comprising in combination a fixture having a plurality of ports in axial alignment therewith, the latter constituting flushing means for the said fixture, a depending nozzle projecting from the uppermost of said ports, a substantially horizontal baffle positioned transversely between said ports and having an aperture in substantial axial alignment therewith, the distance between the end of the said nozzle and the said aperture being at least equal to the diameter of the said nozzle, a housing upon said fixture enclosing the said ports and the said baffle, having vent openings on the walls of the side and rearward portions thereof, the said nozzle and said baffle being positioned above the highest attainable water level within said fixture and a hood over the said vents.

6. In air relieving means of the character described, comprising in combination a fixture to be flushed, a plurality of flushing ports in axial alignment and of substantially uniform size, an intermediate substantially horizontal baffle positioned transversely between said ports and having a receiving aperture in substantial axial alignment therewith, a housing integral with said fixture enclosing said inlet supply ports and said baffle, a coaxial throat portion projecting within said housing, annularly positioned baffle means around said throat portion, the said housing comprising substantially transversely extending vent openings in direct communication with the atmosphere, both housing and said vent openings in their communication with atmosphere being at a level above the rim of the said fixture.

7. In air relieving means of the character described, comprising in combination a fixture, a plurality of flushing ports therefor in axial alignment, an intermediate substantially horizontal baffle positioned transversely between said ports and having central drain means discharging into one of said flushing ports, a housing cooperating with said fixture to enclose the said inlet supply ports and said baffle, the said housing comprising venting means directly communicating with the atmosphere, the said housing and the said vent communicating means being positioned above the rim of the said fixture.

8. In a vacuum breaker, comprising in combination a fixture having a plurality of ports in substantial axial alignment, the latter constituting flushing means for the said fixture, a spud projecting from the uppermost of said ports, an annular baffle surrounding an inner portion of the said spud, a substantially horizontally extending baffle positioned between said ports and

having an aperture in axial alignment therewith, a housing enclosing said ports and the said baffles, the said housing having vents in communication with the said ports above the rim of the said fixture.

- 5 9. In a vacuum breaker, comprising in combination a rimmed fixture, a superposed housing therefor, the said fixture having substantially coaxial flushing ports with said housing arranged to provide a substantially vertical flushing stream, baffles and vents within said housing positioned above the rim of the said fixture, the said vents being in communication with said ports, the said housing being open to atmosphere 10 on all sides except that side immediately adjacent to the fixture.

15 10. In an integral vacuum breaker, comprising in combination a rimmed fixture having a plurality of substantially coaxial flushing ports, a superposed housing therefor enclosing said flushing ports, respective annularly positioned and transversely ported baffles therebetween within the said housing, the said baffles being positioned above the rim of the said fixture, vents in communication with said ports, the said baffles being so arranged whereby the splashing of the flushing water outwardly into the atmosphere through the vents is prevented.

20 11. In an integral vacuum breaker, comprising in combination a rimmed fixture having a plurality of substantially coaxial flushing ports, respective annularly positioned and transversely ported baffles between said flushing ports, the said transversely ported baffle being substantially horizontally extending, the said baffles and flushing ports of the baffle being positioned above 25 the rim of the said fixture, air vents communicating with the atmosphere at substantially the same level in communication with said ports.

25 12. In a vacuum breaker comprising in com-

binion a rimmed fixture having a plurality of supply ports in substantial axial alignment, the latter constituting flushing means for the said fixture, a baffle positioned transversely between said ports, having an aperture in axial alignment therewith and positioned above the rim of the said fixture, a housing superposed upon said fixture enclosing the said ports and the said baffle, the said housing through its walls having venting means in direct communication with the atmosphere, the said vents being positioned on the side and rearward portions thereof, the said port communicating means being positioned wholly above the rim of the fixture.

15 13. In a vacuum breaker comprising in combination a fixture to be flushed having a plurality of substantially vertical extending coaxial flushing ports, a housing having respective annularly positioned and transversely ported baffles between said flushing ports, the said baffles and flushing 20 ports of the baffles being positioned above the rim of the said fixture, air vents communicating with the atmosphere at substantially the same level in communication with the said ports, the said housing having hooded overhanging portions 25 adjacent said vents whereby the latter are normally concealed from view.

14. In a vacuum breaker comprising in combination a fixture to be flushed having a plurality of substantially vertical extending coaxial flushing ports, respective annularly positioned and transversely ported baffles between said flushing ports, a removable unit consisting of a portion of said ports and said baffles, all of said baffles and a portion of said flushing ports being positioned above the rim of the said fixture, air vents communicating with the atmosphere at substantially the same level in communication with the said ports.

ROY H. ZINKIL 40
